SHOE

Francisco Vicente, Habana, Cuba

Application July 8, 1932. Serial No. 621,477

2 Claims. (Cl. 36—14)

This invention particularly relates to sporting shoes made of canvas, leather or any analogous material, and to economic shoes similar to those known as "tennis shoes" which serve for various 5 sports and other purposes, and it has for its object the provision of shoes made of any suitable material which have a sole of raw-rubber which is stuck to the body of the shoe in a suitable manner, and having no seam between the insole and outer sole, but the materials are stuck in cold, 10 whereby a flexible, light, durable and economic shoe is obtained.

The invention is described with reference to the figures of the annexed drawing, of which:

15 Fig. 1 is an outer side elevation of a shoe provided with the improvement forming the subject-matter of this invention, but without the protecting strap for the raw-rubber binding fastening the outer sole to the vamp.

20 Fig. 2 is an enlarged vertical cross-section of same on line 2—2 of Fig. 1.

Fig. 3 is a similar view to Fig. 1, but showing the shoe provided with the protecting strap for the binding fastening the outer sole to the vamp.

25 Fig. 4 is a fragmentary side elevation of the shoe having certain portions unglued and displayed to show the protecting strap for the binding fastening the outer sole to the vamp.

And Fig. 5 is an enlarged fragmentary vertical 30 cross-section of the shoe on line 5—5 of Fig. 4.

The improved construction constituting the subject matter of this invention consists in providing the shoe, for instance a shoe the vamp 1 of which is made of canvas, leather or a like material and having its lower portion bent inwards, with a sole 2 of raw rubber, a heel of the same material 3 in the form of a wedge or a superposed piece, although the heel can be omitted, and a binding 4 of raw rubber bent about the bent 35 portion of the vamp and secured to the vamp 1 on one side and to the outer sole 2 and to the heel 3 on its other side, by means of a rubber solvent, such as gasoline or benzene, or by means of a glue made with either of said rubber solvents. The 40 shoe is provided with an insole 5 of rubber, leather or another material, which is glued to the sole and to the edging of the vamp 1.

By such construction a shoe is obtained which 45 is impermeable at its base, very light, and also economic on account of the nature of the materials of which it is formed and of the low cost of manufacturing the same.

Under certain conditions, in the use of the 50 shoe, the binding 4 might become unglued from the vamp 1 at its upper edge, either because of

the grasping with the nails in an attempt to unfasten it, or else on account of friction with any other body and thereby the ruin of the shoe would commence. This is avoided by protecting means shown in Figures 3 to 5, which consist in 60 a protecting strap 6, preferably made of leather and turned over the upper edge of the binding 4 and held with its inner edge between the binding 4 and the vamp 1 to which it is secured by a seam 65 or otherwise and its outer edge abutting the upper edge of a raw rubber cover 8 which lays upwards from beneath the sole 2 and the heel 3. The binding 4 and the cover 8 are stuck one to the other and each to the sole 2 by means of cold benzene or a glue containing that solvent or any 70 other rubber solvent.

What I claim is:

1. A shoe having a sole of raw rubber, a binding of the same material secured to the sole at one edge and to the vamp at the other edge, a protecting strap between the binding and the vamp and turned over the upper edge of the binding, and a cover of raw rubber laid from the outer edge of the protecting strap to beneath the sole.

2. A shoe having a sole of raw rubber, a binding of the same material secured to the sole at its inner edge and to the vamp at its outer edge, a leather protecting strap stitched to the vamp between the binding and the vamp and turned over the upper edge of the binding to which it is 80 secured by a rubber solvent, and a raw-rubber covering abutting the outer edge of the protecting strap and laying downwards to beneath the sole, said cover being secured by a rubber solvent 85 to the binding and to the sole.

FRANCISCO VICENTE.
